UNITED STATES PATENT OFFICE.

ROBERT E. L. JANNEY, OF CHICAGO, ILLINOIS, ASSIGNOR TO AMERICAN STEEL
FOUNDRIES, OF NEW YORK, N. Y., A CORPORATION OF NEW JERSEY.

CAR-COUPING.

1,135,527.

Specification of Letters Patent. Patented Apr. 13, 1915.

Application filed April 3, 1913. Serial No. 758,601.

To all whom it may concern:

Be it known that I, ROBERT E. L. JANNEY, a citizen of the United States, and resident of Chicago, in the county of Cook and State of Illinois, have invented certain new and useful Improvements in Car-Couplers, of which the following is a specification.

My invention relates to car couplers and has particular reference to a novel knuckle and coöperating wedge lock.

In the application of E. P. Kinne, Serial No. 716,939, filed August 26, 1912, there was disclosed a coupler having a wedge lock, said lock coöperating with a knuckle having pulling lugs, the pulling faces of which lugs were eccentric to the pivot pin, the action of the wedge lock tending to force the eccentric lugs into close engagement with similar surfaces on the coupler head. Thus the knuckle was held tightly closed and pulling strains were transferred to the pulling lugs and removed from the pivot pin. It has been found in practice that such an arrangement is satisfactory under ordinary conditions the exception being the condition in which the wedge lock is held in partially raised position, being caught in this position sometimes by back-lash and other times by creeping, in which case the pulling lugs are ineffective and the entire pulling strain falls on the pivot pin. This tends to deflect or break the pin and it is to the overcoming of such objections that the present invention is directed.

It will be noted that in the present construction the pulling lugs are concentric with the pivot pin. Also that some clearance is allowed between the pivot pin and the walls of the aperture through the knuckle hub. A result of this arrangement is that the pulling strains are taken directly by the pulling lugs irrespective of the position of the knuckle or the location of the wedge lock. In the normal position, the wedge lock will tightly close the knuckle against the stops. However it frequently happens in coupling on curves or due to back-lash in coupling that the lock is caught in mid-position. Because of the wedge construction of the lock the knuckle remains partially open and without the concentric pulling lugs the pulling strains would be taken up by the pivot pin.

The invention will be more readily understood by reference to the accompanying drawings, wherein,

Figure 1 is a plan view of a coupler constructed in accordance with my invention; Fig. 2 is a transverse vertical section showing a preferred form of wedge lock; Fig. 3 is an inverted plan view partly in section, 60 showing the bottom pulling lug, and, Fig. 4 is a longitudinal vertical section showing the pulling lugs more clearly.

Referring more particularly to the drawings it will be seen that I provide a coupler head 10, having a knuckle 11, pivoted to the head by means of a pin 12, there being considerable clearness 13, between the pin and the walls of the apertures through the knuckle. On the interior wall of the coupler head I 70 provide guides 14, slightly inclined from the vertical, with which a lock 15 coöperates, the portion of the lock contacting the guides 14 being shaped to correspond to the angle of the guides. The knuckle is provided with a 75 tail 16, having a locking face 17, against which the locking block abuts when in locking position. A knuckle thrower 18 is pivoted within a coupler head and is adapted to be rotated by contact with the upper edge of 80 the lock when the lock is lifted to unlocking position. Also formed on the inner wall of the coupler head are projections or ribs 19, 20, having the rear face thereof formed by an arc concentric with the pivot pin. These 85 ribs extend into the plane of the knuckle tail and coöperate with similar ribs 21, 22, formed on the upper and lower faces respectively of the knuckle tail. The forward surfaces of the ribs 21, 22, are likewise curved 90 to correspond to the curvature of the ribs 19, 20, the surfaces being in contact during the pulling action. This is clearly shown in Figs. 1 and 3, in which the knuckle is pulled forward to its extreme limit, the coöperating ribs on the head and knuckle tail being in engagement, the knuckle not being 95 in engagement with the pivot pin.

In case the lock is only partially seated the knuckle will not be entirely closed due to the 100 fact that the lower end of the lock is of lesser cross section than the upper end. However, the pulling lugs will be in intimate contact and pulling strains will be taken up thereby as completely as when the knuckle is fully closed. Under buffing strains the blow is 105 preferably taken up by the contact of the hub portions 23 with the ears 24, although the coöperating ribs are arranged to take up such blows if desired. In such case the 110

buffing blow will be taken up partially by the upstanding rib 25, as shown in Fig. 4. It will be seen that by the arrangement shown, the pulling force is taken up by the pulling lugs irrespective of the position of the knuckle, no strain being thrown on the pivot pin.

It is obvious that modifications may be made and such modifications as are within 10 the scope of my claims I consider within the spirit of my invention.

I claim:

1. In a car coupler, the combination of a head, a pivoted knuckle having a tail, a 15 wedge lock for said knuckle, and coöperating abutments on said head and tail, said abutments being curved, the curve being substantially concentric with the knuckle pivot,

whereby pulling force is taken up by the abutments when said lock is partially seated, 20 substantially as described.

2. In a car coupler, the combination of a head, a knuckle pivoted in said head there being substantial clearance between the pivot pin and the knuckle, a wedge lock, a pulling 25 lug having a surface substantially concentric with the pivot pin, said pulling lug coöperating with a similarly curved abutment on said knuckle tail whereby pulling strains are taken up by said lug when said lock is 30 partially seated, substantially as described.

ROBERT E. L. JANNEY.
